UNITED STATES PATENT OFFICE.

JOHN F. HAVEMEYER, OF ARDSLEY-ON-HUDSON, NEW YORK.

BAR-SPACER.

1,372,226.

Specification of Letters Patent. Patented Mar. 22, 1921.

Application filed March 26, 1920. Serial No. 368,897.

To all whom it may concern:

Be it known that I, JOHN F. HAVEMEYER, a citizen of the United States, and a resident of Ardsley-on-Hudson, county of Westchester, State of New York, have invented an Improvement in Bar-Spacers, of which the following is a specification.

The present invention relates to bar supporting and spacing means for use in concrete construction.

Among other objects, the invention provides a combined bar support and spacer, which may be made up in standard lengths regardless of the requirement of any particular building in which it may be used, and which may contain a minimum weight of metal. This spacer may be easily and cheaply manufactured in large quantities.

Further objects of the invention will appear from the following description of a preferred embodiment thereof.

For the purpose of illustration and description, a preferred embodiment of the invention has been selected and shown in the accompanying drawings, wherein,

Figure 1 and Fig. 2 are respectively a top plan view and the side elevation of a bar support and spacer constructed in accordance with the invention,

Fig. 3 is a typical cross-section,

Fig. 4 is an enlarged elevation of the spacer showing a reinforcing bar in section supported thereon,

Fig. 5 is a cross-section of the spacer showing the bar in elevation.

Referring to the drawings, Figs. 1, 2 and 3 show the general construction of the device. The combined support and spacer which for convenience will be referred to as a spacer, is preferably made from ordinary drawn wire 1 of comparatively heavy gage. The wire is bent or formed into the various shapes shown in the accompanying drawings. This bending may be done by any suitable machine so that an indefinite number of properly spaced supports or supporting legs 2 are formed. These supports or legs may be bent alternately to opposite sides of a vertical plane as shown in Figs. 1 and 3 so that the device will stand properly upon the centering. The supports may be bent at different angles so that the reinforcing bars may be placed at any desirable distance above the centering. If desired the supports or legs may be made of various lengths in order to obtain various heights

of the spacer above the centering. The supports are connected by straight, horizontal runs 3, 4, 5, etc., of the wire as shown. The point of bending the wire to form the supports may be at uniform or varied intervals. The supports are formed by bending the wire at points 6 and 7 to form one of the supports or legs and is then bent to a horizontal position forming a seat 8 and then at points 9 and 10 to form another support. The wire may be straight between the points 6 and 7 or it may have an extra bend therein as shown at point 11 in Fig. 3. The wire may be bent in suitable manner and at any angle so long as there are suitably formed supports and seats.

The invention is not to be understood as being limited to the precise form of supports and seats as heretofore described as it is possible to form a single leg bent in one direction and to form a seat therewith, and to form at some further distance along the wire a single support bent in another direction and to form a seat therewith. It is also to be understood that seats may be formed at any position desirable along the length of the wire. For purposes of illustration and description and to show a three-point support of the usual reinforcing bar, the seat for said bar is shown as being between any two supporting legs so that the bar will rest on the seat 8 and will generally contact with the wire near the bends 6 and 10. The length of this seat may be made for a relatively large bar and then used to support reinforcing bars of smaller diameter. In such case, if desired, the points of bending of the wire at 6 and 10 may be brought nearer together, by the bending machine or this bending may be performed on the job.

A reinforcing bar 12 is shown in position in Figs. 4 and 5 as being supported at three points. This, however, is not necessary although desirable. The wire 13 is provided to maintain the reinforcing rod in position, and in this instance, the wire is shown as being wrapped around seat 8 with its ends 14 and 15 extending upwardly on each side of wire 1 as shown in Fig. 3. It is, however, immaterial as to the manner in which the holding wire is attached to the supporting wire. For instance, it may be placed under bends 6 and 10 and brought up over the reinforcing bar. This holding wire may be placed on the spacer before shipment from the factory or it may be at

tached after the spacer and rods are in position. The holding wires are bent around each other after surrounding the reinforcing bar and may be tightened as secure as 5 wished to hold the bar in position.

In forming the spacer, any ordinary rolled steel or spring wire may be employed. The formation of the seats may be at any desired distance away from the center line 10 of the spacer, and may be bent in any desired shape to receive and hold the spacing bars without the use of holding wire or with the use of such a wire. The strength of the wire employed to form the spacer may be determined by the distance apart of the supports and the weight of the reinforcing bars 15 employed. This must be considered in order that the weight of the reinforcing bars used would not spread apart the supports or 20 legs so that the bars would be positioned too near the centering.

Such a spacer for reinforcing bars is of great commercial value and the spacer may be formed of any particular size wire and 25 of any particular length, and the same may be nested together for shipping purposes.

I claim:

1. A bar spacer composed of a single, continuous length of relatively stiff wire, pairs 30 of loops formed from said wire, said loops being angularly disposed in different in-

clined planes to form chairs, and means for securing a bar on said spacer.

2. A bar spacer composed of a continuous strand of wire bent to provide lateral loops, the immediately adjacent loops being angularly disposed in different inclined planes to form an A-shaped chair, the wire being of sufficient stiffness to insure stability of the loops against normal lateral and longitudinal strains without additional tying means. 40

3. A bar spacer composed of a single, continuous length of relatively stiff wire, two closely contiguous loops being formed 45 from said wire, said loops lying in inclined planes at such angle to each other as to form a stable structure, and means for securing a reinforcing bar on the spacer above said loops.

4. A bar spacer composed of a single, continuous length of relatively stiff wire, and pairs of loops formed from said wire, said loops being disposed in different inclined planes at such angle to each other as to 55 constitute a stable chair, said planes being parallel to the longitudinal axis of said length of wire.

In testimony whereof I have signed my name to this specification this 25th day of 60 March, 1920.

JOHN F. HAVEMEYER.
